UNITED STATES PATENT OFFICE.

LORING J. BAKER, OF BOSTON, MASSACHUSETTS, ASSIGNOR TO FRANKLIN P. BAKER, OF SAME PLACE.

BIT-STOCK.

SPECIFICATION forming part of Letters Patent No. 250,186, dated November 29, 1881.

Application filed August 20, 1881. (No model.)

To all whom it may concern:

Be it known that I, LORING J. BAKER, a citizen of the United States, residing at Boston, in the county of Suffolk and State of Massachusetts, have invented certain new and useful Improvements in Interchangeable Bit and Drill Stocks; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My present invention relates to compound bit-stocks and multiplying hand-drills—that is, an implement capable of performing either of these functions and interchangeable from one to the other, as occasion requires; and it consists in the employment, in combination with an ordinary bit-stock, of an arbor susceptible of free rotary motion in the head of the stock carrying at its outer end the drill or bit chuck, and at its inner end a toothed pinion which engages and is driven by a spur-gear mounted loosely upon the handle of the stock, said gear being provided with a set-screw by which it may be confined rigidly to the stock when a carpenter's bit is to be used, and the whole being so arranged that when the bit-stock is in use and the gear is free to rotate about the handle of such stock the gear actuates the pinion to rotate the drill-chuck with an increased or multiplied movement, but when the gear is locked to the stock it rotates with it and has no effect upon the pinion and chuck and the implement becomes a simple bit-stock.

The drawings accompanying this specification represent, in Figure 1, a longitudinal section of an implement containing my improvements. Fig. 2 is an end elevation; and Fig. 3 represents a modified construction of the handle of the stock.

In these drawings, A represents the body or frame of an ordinary carpenter's bit-stock, the tubular head of the stock which supports the bit or drill arbor being shown at B, the handle of such stock at C, its swiveled bearing-plate at D, and its lateral arms at a and b.

In carrying out my invention I employ a

straight arbor or spindle which is deposited in the bore of the head B, so as to rotate freely in the latter, and carries at its outer end a chuck, E, for holding the drills or bits, while at its inner end, and inside of the arm a of the stock, this arbor C' has affixed to it a toothed pinion, F, which engages a spur-gear, G, loosely mounted upon the handle C of the stock, at the front end of the latter. The arm a of the bit-stock is, for convenience of manufacture, formed independent of the handle C, and secured to the latter in a proper manner, in lieu of being cast or forged integral with it.

A set-screw, H, is screwed through one of the arms of the gear G in order, when the instrument is to be used as a bit-stock, to intercept and grasp the arm a of the stock, and prevent the said gear from rotating upon the handle or actuating the pinion F, thereby estopping rotations of the gear and pinion upon their axes and holding them fast to the stock. In the present instance the hub c of the gear G is part and parcel of a loose handle, I, which incloses the handle C of the stock, but the said handle I may be independent of the said hub, as shown in Fig. 3, in which case the user of the instrument must grasp the head of the set-screw with his thumb in order to prevent slip movement between such handle and the said gear.

The hub c of the gear may be integral with the body of the latter, as shown in Fig. 3 of the drawings, or screwed to it, as shown in Fig. 1, or otherwise secured to it.

When the implement is to be used as a carpenter's bit-stock the set-screw H is advanced until it intercepts the arm a of the stock and clamps the gear G to such arm. Under these circumstances neither the gear G nor pinion F can rotate upon its axis, but both are compelled to remain stationary upon or with the stock, and practically constitute part of the latter, and no rotary movement of the bit within or with respect to the stock takes place.

When the implement is to be used as a machinist's multiplying hand-drill the set-screw is retracted and the gear G allowed to rotate upon the handle C of the stock. Under these circumstances a complete rotation of the handle C bodily, and with it the gear, effects not only

multiplied rotations of the pinion F and arbor C' to the extent due to the differential size of the said pinion and gear, but the rotation of the gear bodily with the handle C and about the pinion effects an additional rotation of such pinion and of the drill-chuck.

I claim—

1. In combination, the head B, constituting a support to the arbor C', and having the arm 10 or crank *a*, and wrist-pin or handle C, the arbor C', pinion F, secured to such arbor, the gear G, mounted loosely upon the wrist-pin or handle C, and the set-screw H, or its equivalent, screwing through the gear and adapted to intercept 15 and grasp the arm or crank *a*, the whole be-

ing in manner and operating substantially as stated.

2. As co-operative parts of an interchangeable bit-stock and hand-drill, the stock having the members B C D *a b*, the arbor C', the pinion F, secured to such arbor, the gear G, engaging the pinion F and pivoted upon the handle C, and the set-screw H, adapted to operate substantially as and for the purpose set forth. 20

In testimony whereof I affix my signature 25 in presence of two witnesses.

LORING J. BAKER.
